UNITED STATES PATENT OFFICE.

FRANK W. KRINGEL, OF LOS ANGELES, CALIFORNIA.

PIANO WITH AUXILIARY HARMONIC SOUNDING-BOARD.

SPECIFICATION forming part of Letters Patent No. 732,304, dated June 30, 1903.

Application filed February 18, 1901. Serial No. 47,871. (No model.)

To all whom it may concern:

Be it known that I, FRANK W. KRINGEL, a citizen of the United States, residing at Los Angeles, in the county of Los Angeles and State of California, have invented a new and useful Piano with Auxiliary Harmonic Sounding-Board, of which the following is a specification.

The object of this invention is to give a more powerful and sustaining tone. This I accomplish by means of strings provided with a fundamental sounding portion and a harmonic portion in combination with a harmonic sounding-board arranged above or beyond the plate-bridge, said sounding-board being provided with suitable means for holding the harmonic member of the string in relative sounding interval with the fundamental sounding member of the string. I preferably provide adjustable means connected with said sounding-board for holding the harmonic member of the string in relative sounding interval with said fundamental sounding member of the string. I also provide a plate which is fundamentally novel in that it is provided above or beyond the plate-bridge with a sounding-recess.

The accompanying drawings illustrate my invention. Figure I is a fragmental front view of an upright piano embodying my invention. Fig. II is a fragmental end elevation of the same, partly in section. Fig. III is a fragmental sectional elevation of my invention as applied in a grand piano looking toward the last string of the treble.

a indicates the plate of the piano furnished with a sounding-recess 4.

b indicates the main sounding-board.

c indicates the main or sounding-board bridge.

d indicates the wrest-plate bridge.

e indicates the pin-block.

f indicates the strings.

g indicates the auxiliary harmonic sounding-board arranged over the recess 4 adjacent to the wrest-plate bridge d.

1 and 2 indicate, respectively, the main or fundamental portion or member and the harmonic portion of the strings, which are adapted to be stretched over the sounding-boards and by reason of their arrangement therewith

to improve the quality and increase the power and tone of the instrument.

h indicates means connected with the harmonic sounding-board for holding the harmonic member 2 of the string in relative sounding interval with the fundamental sounding member 1 of the string. Such means preferably consist of the auxiliary bridge-body 3, resting on the harmonic sounding-board g, which rests on the iron plate a above the sounding-recess 4 therein between the wrest-plate bridge d and the pin-block e.

5 indicates an agraffe, through which the string passes and which is screwed into the auxiliary bridge and sounding-board 3 and g.

6 indicates an upper string-rest, and 7 an adjustable lower string-rest, arranged respectively above and below the agraffe 5.

i indicates the tuning-pin; j, the hitch-pin; k, the hammer.

m indicates the ordinary deadening-strips, of cloth, to prevent vibration of the strings above the harmonic members 2 and below the fundamental sounding members 1.

In practice the harmonic member 2 of the string can be accurately tuned relative to the fundamental member 1 by shifting the string-rest 7. The tone produced by this new piano 80 is distinguished by its superior strength, quality, and resonance.

n indicates the frame-timbers, and o indicates the sounding-board-supporting strips, which are arranged in the ordinary manner 85 on the frame-timbers n to support the ordinary sounding-board b.

The uppermost string-rest q rests upon the upper edge of the auxiliary sounding-board, which edge is supported by the wrest-plate a. 9c The plate-bridge d in the form shown in Figs. I and II rests upon the lower edge of said auxiliary sounding-board, which edge is also supported by the plate a. The pressure of the strings on the string-rest q and the wrest-plate bridge d keeps the auxiliary sounding-board in place on the frame and over the recess 4.

In the grand piano shown in Fig. III the wrest-plate bridge d is upon the side of the strings opposite the sounding-boards and the auxiliary recess and sounding-board are beyond or to the rear of the wrest-plate bridge; instead of above it, as in the upright piano;

- but in either construction the string-rest 7 can be so moved or adjusted relatively to the wrest-plate bridge *d* that when the string is tuned the auxiliary portion will be of such 5 length that it will vibrate in harmony with the fundamental portion, which vibration will be taken up and intensified by the auxiliary sounding-board, and thereby add materially to the volume and duration of the tone.
10. What I claim, and desire to secure by Letters Patent of the United States, is—
1. In a piano, a main sounding-board and bridge, strings, each provided with a fundamental sounding member and a harmonic member, a harmonic sounding-board arranged adjacent to the wrest-plate bridge; said sounding-board being provided with suitable means for holding the harmonic member of each string in relative sounding 15 interval with the fundamental sounding member.
  2. A piano furnished with a main sounding-board and bridge, strings, each provided with a fundamental sounding member and a harmonic member, a harmonic sounding-board arranged adjacent to the wrest-plate bridge, and adjustable means connected with said sounding-board for holding the harmonic member of each string in relative sounding 20 interval with the fundamental sounding member.
  3. In a piano, the combination of a plate furnished with a sounding-recess; a main sounding-board and bridge; the wrest-plate bridge; the pin-block; the strings each provided with a fundamental sounding member and a harmonic member; an auxiliary harmonic sounding-board arranged adjacent to the wrest-plate bridge; and means connected 25

with said sounding-board for holding the harmonic member of each string in relative 40 sounding interval with the fundamental sounding member.

4. A piano provided with a main sounding-board and a recess adjacent thereto, strings provided with a fundamental sounding portion and a harmonic portion, the fundamental portion of the strings extending over the main sounding-board and the harmonic portion extending over the recess. 45

5. A piano provided with a main sounding-board and a recess adjacent thereto, an auxiliary sounding-board over the recess, strings provided with a fundamental sounding portion and a harmonic portion, means for supporting the fundamental portion of the strings 50 over the main sounding-board, and means for supporting the harmonic portion over the auxiliary sounding-board.

6. A musical instrument provided with a main and an auxiliary sounding-board, 60 strings, each provided with a fundamental sounding portion, and with a harmonic portion, means for supporting the fundamental portions of the strings over the main sounding-board and means for supporting the harmonic portions over the auxiliary sounding-board. 65

In testimony whereof I have signed my name to this specification, in the presence of two subscribing witnesses, at Los Angeles, 70 California, this 8th day of February, 1901.

FRANK W. KRINGEL.
